UNITED STATES PATENT OFFICE.

JACOB S. ERICKSEN, OF CHICAGO, ILLINOIS, ASSIGNOR TO FERGUSON AND LANGE FOUNDRY COMPANY, OF CHICAGO, ILLINOIS, A CORPORATION OF ILLINOIS.

WATER-HEATING APPARATUS.

Application filed September 5, 1922. Serial No. 586,188.

To all whom it may concern:

Be it known that I, JACOB S. ERICKSEN, a citizen of the United States, residing at Chicago, in the county of Cook and State of Illinois, have invented certain new and useful Improvements in Water-Heating Apparatus, of which the following is a specification.

My invention relates to apparatus for heating water, more particularly to an apparatus adapted to be used in conjunction with the heating boiler of a home, apartment building, hotel, institution or the like, and to furnish a supply of hot water.

The primary object of my invention is the provision of water heating apparatus of the general type referred to which will be relatively simple in construction, easy and inexpensive to install, efficient in operation, economical in fuel consumption, require but little attention to operate, inexpensive to maintain in operation, will reduce fire hazards, and which will serve to maintain a supply of hot water of substantially uniform temperature for wash basins or other fixtures available for immediate use; and, to this end, the invention preferably contemplates the provision of a storage tank connected with a source of cold water supply, a water heater adapted to be positioned in a receptacle containing a heating medium, for example, a hot water circulating boiler, a steam generating boiler, or the like, in such manner that the heater will be subject to the heating action of the medium, a circulating system so connected with the storage tank and the heater that cold water will flow from the lower portion of the tank to the heater where it will be heated and then flow to and be discharged into the upper portion of the tank, and a hot water circulating consumption system so connected with the storage tank and the first mentioned system that hot water will flow continuously from the storage tank through the consumption system and be returned to the water heater. Water heating apparatuses for furnishing hot water to apartment buildings, hotels, institutions and other buildings where a considerable quantity of hot water is used are ordinarily specially designed for each building, which materially increases the cost of the apparatus and its installation. It is a further object of my invention to provide apparatus for this purpose the construction

of which will be standardized to a very large extent so that the apparatus may be made in various sizes to suit the requirements of the different buildings and the various parts comprising the apparatus, may be manufactured in quantities and carried in stock, whereby the cost and the installation of the apparatus will be reduced to a minimum. With this in view, my invention preferably contemplates providing, in addition to the usual parts comprising the apparatus, an independent receptacle in which one or more water heaters connected to the apparatus mentioned may be installed, said receptacle being so connected with the heating boiler that the heating medium may circulate from the boiler, through the receptacle and back to the boiler. This feature of my invention is particularly advantageous where the heating boiler is of the sectional type and it is impractical to install the water heater directly in the boiler. In the case last mentioned, the various sections of the heating boiler adjacent their upper ends are connected by a system of pipes with the receptacle containing the water heater and the heating medium is returned from said receptacle to the boiler in substantially the same manner as the feed water flows into the boiler, and the efficiency of the heating boiler is materially increased.

It is a further object of my invention to connect the pipes comprising the hot water circulating consumption system with the storage tank and the circulating system connecting the storage tank and the heater in such manner that the formation of air pockets in the last mentioned circulating system will be prevented and a continuous flow of water in this system insured.

A further object of my invention is the provision of means whereby the storage tank will not be by-passed when hot water is drawn from the consumption circulating system; and, to this end, a very sensitive check valve is provided in the return pipe of the consumption circulating system which is so constructed that, upon reversal of the flow of water in said pipe, said valve will instantly close, and any water taken from the consumption system will be drawn directly from the storage tank.

A further object of my invention is the provision of a system of piping connecting the storage tank with the water heater so

arranged that the pipes may easily be cleaned and kept free of mud or sediment. To this end, the system is so arranged that most of the mud or sediment in the water 5 will not be permitted to get into the entire system aforesaid but will be confined to certain portions thereof which are constructed in such manner that the mud or sediment may be easily removed, and the remaining 10 portions of the system are so arranged that the mud or sediment which is deposited in the water heater and the pipes leading to and from the heater may be easily flushed out.

15 The invention consists in the novel constructions, arrangements and devices to be hereinafter described and claimed for carrying out the above stated objects and such other objects as will appear from the following description of certain preferred embodiments illustrated in the accompanying drawings, wherein—

Fig. 1 is a diagrammatic view of water heating apparatus embodying the principles 25 of my invention;

Fig. 2 is a diagrammatic view of a portion of the apparatus and illustrating a modified arrangement whereby the formation 30 of air pockets in the circulating system connecting the storage tank with the water heater will be prevented;

Fig. 3 is a diagrammatic view of water heating apparatus embodying the principles 35 of my invention and connected to a boiler of the sectional type;

Fig. 4 is a side elevational view, on an enlarged scale, of my preferred form of water heater installed in a heating boiler of ordinary construction, certain parts being broken away to show the internal construction;

Fig. 5 is a longitudinal sectional view, on a further enlarged scale, of the water heater;

Fig. 6 is a sectional view, on an enlarged scale, of a portion of the apparatus illustrating the preferred arrangement whereby the formation of air pockets in the circulating system connecting the storage tank 50 with the water heater will be prevented;

Fig. 7 is a longitudinal sectional view, on an enlarged scale, of the preferred form of check valve employed in the return pipe of the consumption circulating system;

Fig. 8 is a transverse sectional view taken on the line 8—8 of Fig. 7;

Fig. 9 is a sectional view of a modified form of check valve which may be employed in the return pipe of the consumption circulating system; and

Fig. 10 is a sectional view taken on the line 10—10 of Fig. 9.

Like characters of reference designate like parts in the several views.

65 Referring now to the drawings, and par-

ticularly to the diagram shown in Fig. 1 thereof, it will be seen that the apparatus includes a storage tank 12 supplied with cold water by means of a pipe 13 leading from a source of supply under pressure 70 and which terminates a short distance above the bottom of the tank. The tank 12 is connected with a water heater, designated generally by the reference character 14 and positioned in the heating boiler 15, by a 75 plurality of pipes, including a substantially vertically disposed stand pipe 16 the upper end of which projects upwardly through and terminates a substantial distance above the bottom of the tank and the lower end 80 of which is provided with a shut-off cock 17. The pipe 16 is provided with a fitting 18 from one side of which extends a horizontal pipe 19 connected by a T-shaped fitting 20 with a relatively short pipe 21. The 85 pipe 21 is connected by means of a T-shaped fitting 22 with a horizontally extending pipe 23. A T-shaped fitting 24 is provided on one end of the pipe 23 and is connected by a pipe 25 with the water heater. The 90 pipe 26 is connected at its lower end to the water heater and at its upper end to a T-shaped fitting 27. A horizontally extending pipe 28 is connected at one end to the fitting 27 and at the other end to a T-shaped 95 fitting 29, the latter being connected by a pipe 30 with the storage tank.

The hot water circulating consumption system includes a pipe 31 extending to the various places at which the water is used, 100 faucets 32 being provided to draw off the water when desired, the upper end of said pipe 31 being connected to a return pipe 33 which is connected to the pipe 23 by means of a T-shaped fitting 34. The lower end of 105 the pipe 31 is connected by a plurality of pipes 35 with the pipe 36 which extends through the fitting 29, the pipe 30 and into the storage tank 12, the lower end of said pipe 36 extending a substantial distance below the level at which the pipe 30 discharges 110 into the tank. A recording thermometer 37 may be connected in the hot water consumption system if desired. A check valve, designated generally by the reference character 115 38, is preferably provided in the return pipe 33. A cold water supply pipe 39 ordinarily extends alongside the pipe 31 but, as this pipe forms no part of the apparatus, its various connections and outlets have not 120 been illustrated.

The water heater is shown in detail in Fig. 5, and the manner of installing it in an ordinary heating boiler is illustrated in Fig. 4. The heater includes a cast hollow head 125 40 provided with a partition 41 which is formed so as to provide chambers 42 and 43 in the head. One wall of the chamber 42 is provided with an opening 44 and is threaded for the reception of the cold water 130

inlet pipe 25. One wall of the chamber 43 is provided with an opening 45 also threaded for the reception of the hot water discharge pipe 26. The inner side of the head 40 is 5 provided with a flange 46 adapted to be placed against the face of the boiler, see Fig. 4, and to be secured thereto by a plurality of cap screws. The flange 46 is provided with an opening 47 and is threaded 10 for the reception of a relatively large pipe 48, which is formed of a non-corrosive substance the heat conductivity of which is relatively high, for example, copper. The head of the heater is provided with an opening 49 so that communication is established 15 between the chamber 43 and the pipe 48. The inner end of the pipe 48 is closed by any suitable means, for example, a cap 50. The partition 41 is provided with an opening 51 20 which is substantially concentrically disposed with respect to the openings 49 and 47, and the pipe 48. The outer end of a relatively small pipe 52 is placed in the opening 51 and said pipe is secured in the partition 41 25 in any desired manner, for example, by turning the outer end of the pipe over the adjacent portion of the partition. The pipe 52 extends inwardly into the pipe 48, the inner end of said pipe 52 being left open 30 and terminating somewhat short of the end of the pipe 48. The pipe 52 is also preferably formed of a non-corrosive substance the heat conductivity of which is relatively high, and, as the walls thereof are quite 35 thin, the pipe is preferably formed of brass to give it the desired strength. The wall of the chamber 42 opposite the partition 41 is provided with an opening 53 threaded for the reception of a plug 54.

40 The cold water flows from the pipe 13 under pressure into the lower portion of the storage tank, flowing therefrom into the chamber 42 of the water heater, thence through the small pipe 52 and is discharged 45 into the inner end of the large pipe 48 where its direction of flow is reversed, the water then flowing out of the pipe 48 into the chamber 43. The course of the water through the heater is indicated by the several arrows 50 in Fig. 5. As the pipe 48 of the heater is subject to the heating action of the heating medium surrounding it, said pipe is heated, and, consequently, the temperature of the water while passing through said pipe will 55 be raised very considerably. The hot water flowing in the pipe 48 transmits heat to the pipe 52 and said last mentioned pipe is heated to a considerable extent. By this arrangement the water is gradually heated 60 as it enters the pipe 52 and is subject to the greatest degree of heat while passing through the pipe 48. Since the heat conductivity of the pipes 48 and 52 is relatively high, the efficiency of the heater is also high.

65 The hot water flows through the pipes 26,

28 and 30 and is discharged into the upper portion of the storage tank. The hot water accumulates in the upper portion of the storage tank and continually circulates through the hot water circulating consumption system, being returned to the heater 70 through the pipes 33, 23 and 25. It will be noted that the lower end of the pipe 36 extends into the storage tank a substantial distance below the level at which the hot water from the pipe 30 is discharged into the tank, consequently, water drawn from the pipe 31 must be taken from the storage tank, as it cannot be drawn directly from the pipes 30 and 28.

75 Referring to Fig. 6 of the drawing, it will be noted that the pipe 36 is provided with a port 36^a which is so located that communication is established between said pipe and the upper portion of the chamber 29^a provided in the fitting 29. This arrangement prevents a column of air being trapped in the pipe 30, fitting 29 and pipe 28, because in drawing water from the pipe 31 any air present in the pipe 80 30, fitting 29 or pipe 28 will be drawn through the port 36^a, thereby insuring free circulation of hot water through the pipes 28 and 30. The same results may be obtained by the arrangement shown in Fig. 90 95 2 of the drawing wherein the lower end of the pipe 31 is connected to a fitting 55, the latter being connected by a pipe 56 with the storage tank and by a pipe 57 with the fitting 29. The parts are so arranged that the point of connection between the pipe 57 and the pipe 31 is not substantially lower than the point of connection between the pipe 57 and the fitting 29. With this arrangement, when water is 100 105 drawn from the pipe 31, any air that may be present in the pipe 28, fitting 29 or pipe 30 will be drawn out through the pipe 57 and into the pipe 31.

110 When hot water is drawn from the pipe 31 the check valve 38 in return pipe 33 prevents the storage tank from being bypassed which might occur if the check valve 38 were not provided. With the check valve 38 in the pipe 33 any reverse flow 115 of water in pipe 33 will be checked. The check valve employed in the return pipe 33 must be very sensitive and is preferably either of the form shown in Figs. 7 and 8 or of the form shown in Figs. 9 and 10. 120

125 Referring to Figs. 7 and 8, the body portion of the check valve consists of a standard T-shaped pipe fitting 58 provided with the usual openings 59, 60 and 61. A bushing 62 provided with external and internal threads is inserted in the opening 60, one portion of the pipe 33 being threaded into the bushing and the other portion of said pipe being inserted into the opening 61. The opening 59 is closed by the screw plug 130

63. A ball float 64 is so positioned within the body 58 that water may flow in the direction indicated by the arrow, see Fig. 7, but is checked whenever the flow is reversed. Movement of the float 64 is restricted by a plurality of prongs 65 which project from the inner side of the bushing 62, the free ends of said prongs being bent over substantially as shown in Fig. 7 so as to engage the float. This type of check valve is inexpensive to manufacture and is extremely sensitive in operation.

The check valve shown in Figs. 9 and 10 comprises a hollow body member 66 provided with openings 67 and 68 into which the ends of the return pipe 33 may be threaded. The body is provided with a seat 69, a gate member 70 being pivoted at 71 to the valve body so that it may freely swing against the seat 69. The gate may be inserted into the body through an opening 72 which is normally closed by a cap member 73. The action of this type of valve is extremely sensitive, the flow of water in a direction opposite to the normal flow as indicated by the arrow shown in Fig. 10 will cause the gate to swing instantly against the seat 69.

30 The manner in which my apparatus may be standardized is illustrated diagrammatically in Fig. 3 wherein it will be noted that the water heater is installed in a receptacle 74 which may be of any desired 35 construction. The receptacle 74 is shown as operatively connected with a heating boiler 75, of the sectional type. The several sections of the boiler are each connected by a pipe 76 with the receptacle 74, the pipes 40 76 preferably being connected to the upper portions of the several boiler sections which permits the heating medium at its highest temperature to flow from the boiler sections into the receptacle 74. The heating medium 45 is returned to the boiler by a pipe 77 in substantially the same manner as the feed water is supplied to the boiler. It is impractical to install the water heater directly in a boiler of the sectional type but, when 50 the receptacle 74 is provided adjacent the boiler, it is a comparatively simple matter to connect the respective boiler sections with the receptacle. Connecting the receptacle 74 with the upper portions of the 55 respective boiler sections and returning the heating medium to the boiler as described greatly increases the circulation of the heating medium through the sections of the boiler and hence increases the efficiency of 60 the boiler. It will be obvious that the receptacle 74 may be readily installed in connection with any type of boiler.

Apparatus embodying the principles of my invention may be made in various sizes 65 to suit the requirements of different build-

ings, and the various parts of the apparatus may be manufactured in quantities and carried in stock, thereby making it unnecessary to design specially the apparatus for each installation. With my apparatus the heating boiler is utilized to heat the necessary amount of hot water required for consumption and it is not necessary to provide a special heater. In water heating systems commonly employed, particularly in large buildings, the water is ordinarily heated by a special heater and, as the demand, on such systems are higher at certain times of the day than at others, for example, in the morning, the janitor will frequently force the heater to such an extent as to overheat it considerably. Many fires have resulted directly from this cause. With my apparatus no extra heater is provided and the fire hazard is considerably reduced.

Heating the water for the consumption system by utilizing the heating boiler materially reduces the amount of fuel used, as it is considerably less expensive to fire a little additional fuel into the heating boiler to compensate for the water heating apparatus than it is to fire two independent boilers. In this same connection it is also to be noted that there is a considerable saving of the janitor's time.

With my apparatus the water heater does not come into direct contact with the fire. The alkalinous deposits in water are not freed unless the water reaches approximately the boiling point. The ordinary heating boilers usually carry a pressure considerably less than fifteen pounds and taking into consideration the transmission losses, it has been found that the temperature of the water in the water heater very rarely exceeds one hundred and ninety degrees, hence the alkali in the water is not freed. This is an important matter, as no scales or crusts are formed in the pipes of the water heater and its efficiency is not impaired. The temperature of the water in the consumption system remains at substantially a uniform temperature.

With proper care the apparatus will last as long as the heating boiler itself and requires no special attention except to flush out the sediment in the main circulating pipes occasionally. By connecting the pipe 16 with the storage tank in the manner heretofore described, a large portion of the sediment in the water will deposit in the bottom of the tank and not pass into the circulating pipes. The sediment deposited in the bottom of the tank may be flushed out of the tank by removing the plug 78. The pipe 16 acts as a collector for a considerable part of the sediment in the water flowing from the tank to the water heater. By opening the cock 17 the sediment present in the pipe 16 may be readily flushed out. It will be

noted that the pipes comprising the circulating system connecting the water heater with the storage tank include a plurality of T-fittings and in the arrangement shown in Fig. 1, for example, the fittings 18, 20, 34, 24 and 27 are provided with plugs 18^a, 20^a, 34^a, 24^a, and 27^a, respectively. By removing any two of these plugs and attaching a hose connected with a source of water supply the sediment in the intermediate sections of pipe may be easily flushed out. The water heater also may be flushed out by removing the plug 54 and attaching the hose.

10 I do not intend to limit my invention to the details of construction, arrangements and devices shown and described except only in so far as certain of the appended claims are specifically so limited, as it will be obvious to those skilled in the art, that modifications may be made without departing from the principles of my invention.

I claim:

1. In combination with a receptacle containing a heating medium, a water heater positioned in said receptacle in such manner that it is subject to the heating action of said medium, a storage tank, water supply means for said heater, a pipe leading from said heater and arranged so that water flowing therein must discharge into the upper portion of said tank, and a hot water circulating system including a pipe having controlled outlet means, said second-named pipe leading from the upper portion of said tank and having its intake end sufficiently remote from the discharge end of said first-named pipe that water flowing into said second-named pipe must be taken from the supply in said tank, and a return pipe leading from the discharge end of said second-named pipe back to said water supply means.

2. In combination with a receptacle containing a heating medium, a water heater positioned in said receptacle in such manner that it is subject to the heating action of said medium, water supply means including a storage tank for said heater, a pipe leading from said heater and arranged so that water flowing therein must discharge into the upper portion of said tank, and a discharge pipe having controlled outlet means, said second-named pipe leading from the upper portion of said tank and having its intake end sufficiently remote from the discharge end of said first-named pipe that water flowing into said second-named pipe must be taken from the supply in said tank.

3. In combination with a receptacle containing a heating medium, a water heater positioned in said receptacle in such manner that it is subject to the heating action of said medium, a storage tank connected to a source of water supply, a pipe leading from the lower portion of said tank to said

heater, a pipe leading from said heater and arranged so that water flowing therein must discharge into the upper portion of said tank, and a hot water circulating system including a pipe having controlled outlet means, said third-named pipe leading from the upper portion of said tank and having its intake end sufficiently remote from the discharge end of said second-named pipe that water flowing into said third-named pipe must be taken from the supply in said tank, and a return pipe leading from the discharge end of said third-named pipe back to said heater.

4. In combination with a sectional boiler adapted to generate a heating medium, a receptacle, conduit means leading from the upper portions of the respective boiler sections to said receptacle and so arranged that the heating medium may flow into said receptacle, means to return said medium to said boiler sections thereby establishing a circulatory system between said receptacle and said boiler sections, a water heater positioned in said receptacle in such manner that it is subject to the heating action of said medium, a storage tank, water supply means for said heater, a pipe leading from said heater and arranged so that water flowing therein must discharge into the upper portion of said tank, and a hot water circulating system including a pipe having controlled outlet means, said second-named pipe leading from the upper portion of said tank and having its intake end sufficiently remote from the discharge end of said first-named pipe that water flowing into said second-named pipe must be taken from the supply in said tank, and a return pipe leading from the discharge end of said second-named pipe back to said water supply means.

5. In combination with a sectional boiler adapted to generate a heating medium, a receptacle, conduit means leading from the upper portions of the respective boiler sections to said receptacle and so arranged that the heating medium may flow into said receptacle, means to return said medium to said boiler sections thereby establishing a circulatory system between said receptacle and said boiler sections, a water heater positioned in said receptacle in such manner that it is subject to the heating action of said medium, water supply means including a storage tank for said heater, a pipe leading from said heater and arranged so that water flowing therein must discharge into the upper portion of said tank, and a discharge pipe having controlled outlet means, said second-named pipe leading from the upper portion of said tank and having its intake end sufficiently remote from the discharge end of said first-named pipe that water flowing into said second-named pipe must be taken from the supply in said tank.

6. In combination with a sectional boiler adapted to generate a heating medium, a receptacle, conduit means leading from the upper portions of the respective boiler sections to said receptacle and so arranged that the heating medium may flow into said receptacle, means to return said medium to said boiler sections thereby establishing a circulatory system between said receptacle and said boiler sections, a water heater positioned in said receptacle in such manner that it is subject to the heating action of said medium, a storage tank connected to a source of water supply, a pipe leading from the lower portion of said tank to said heater, a pipe leading from said heater and arranged so that water flowing therein must discharge into the upper portion of said tank, and a hot water circulating system including a pipe having controlled outlet means, said third-named pipe leading from the upper portion of said tank and having its intake end sufficiently remote from the discharge end of said second-named pipe that water flowing into said third-named pipe must be taken from the supply in said tank, and a return pipe leading from the discharge end of said third-named pipe back to said heater.
7. In combination with a receptacle containing a heating medium, a water heater positioned in said receptacle in such manner that it is subject to the heating action of said medium, water supply means including a storage tank for said heater, a pipe leading from said heater and arranged so that water flowing therein must discharge into the upper portion of said tank, a hot water circulating system including a pipe having controlled outlet means, said second-named pipe leading from the upper portion of said tank and having its intake end sufficiently remote from the discharge end of said first-named pipe that water flowing into said second-named pipe must be taken from the supply in said tank, a return pipe leading from the discharge end of said second-named pipe back to said water supply means, and means communicatively connecting said first-named pipe with said second-named pipe, for the purpose specified.
8. In combination with a receptacle containing a heating medium, a water heater positioned in said receptacle in such manner that it is subject to the heating action of said medium, water supply means including a storage tank for said heater, a pipe leading from said heater and arranged so that water flowing therein must discharge into the upper portion of said tank, a hot water circulating system including a pipe having controlled outlet means, said second-named pipe leading from the upper portion of said tank and having its intake end sufficiently remote from the discharge end of
- said first-named pipe that water flowing into said second-named pipe must be taken from the supply in said tank, a return pipe leading from the discharge end of said second-named pipe back to said water supply means, and means communicatively connecting said first-named pipe at substantially its highest point with said second-named pipe at a point not substantially lower than said first-named point, for the purpose specified. 75
9. In combination with a receptacle containing a heating medium, a water heater positioned in said receptacle in such manner that it is subject to the heating action of said medium, water supply means including a storage tank for said heater, a pipe leading from said heater and arranged so that water flowing therein must discharge into the upper portion of said tank, a chambered fitting provided in said pipe, a hot water circulating system including a pipe having controlled outlet means, said second-named pipe extending through said fitting and that portion of said first-named pipe between said fitting and said tank and having its intake end sufficiently remote from the discharge end of said first-named pipe that water flowing into said second-named pipe must be taken from the supply in said tank, and a return pipe leading from said second-named pipe back to said water supply means, said second-named pipe having a port leading into the upper portion of the chamber in said fitting, for the purpose specified. 80
10. In combination with a receptacle containing a heating medium, a water heater positioned in said receptacle in such manner that it is subject to the heating action of said medium, a storage tank connected to a source of water supply, a pipe leading from the lower portion of said tank to said heater, a pipe leading from said heater and discharging into the top of said tank, a chambered fitting provided in said second mentioned pipe, and a hot water circulating system including a pipe having outlet means and a return pipe leading from said third mentioned pipe back to said heater, the lower portion of said third mentioned pipe extending through said fitting and that portion of said second mentioned pipe between said fitting and said tank and terminating sufficiently below the point of discharge of said second mentioned pipe into said tank so that water drawn from said third mentioned pipe will flow from the tank and not directly from said second mentioned pipe, said third mentioned pipe having a port leading into the upper portion of the chamber in said fitting, for the purpose specified. 95
11. In combination with a receptacle containing a heating medium, a water heater positioned in said receptacle in such manner that it is subject to the heating action of said medium, water supply means including a

- storage tank for said heater, a pipe leading from said heater and arranged so that water flowing therein must discharge into the upper portion of said tank, and a hot water 5 circulating system including a pipe having controlled outlet means, said second-named pipe leading from the upper portion of said tank and having its intake end sufficiently remote from the discharge end of said first- 10 named pipe that water flowing into said second-named pipe must be taken from the supply in said tank, a return pipe leading from the discharge end of said second-named pipe back to said water supply means, and a 15 check valve in said return pipe, for the purpose specified.
12. In combination with a receptacle containing a heating medium, a water heater positioned in said receptacle in such manner 20 that it is subject to the heating action of said medium, water supply means including a storage tank for said heater, a pipe leading from said heater and arranged so that water flowing therein must discharge into the upper 25 portion of said tank, a hot water circulating system including a pipe having controlled outlet means, said second-named pipe leading from the upper portion of said tank and having its intake end sufficiently remote from the discharge end of said third-named pipe that 30 water flowing into said fourth-named pipe must be taken from the supply in said tank, and a return pipe leading from the discharge end of said fourth-named pipe back 35 to said water supply means.
13. In combination with a receptacle containing a heating medium, a water heater positioned in said receptacle in such manner 40 that it is subject to the heating action of said medium, water supply means including a storage tank for said heater, a pipe leading from said heater and arranged so that water flowing therein must discharge into the upper portion of said tank, a hot water circulating system including a pipe having controlled outlet means, said second-named pipe leading from the upper portion of said tank and having its intake end sufficiently remote 45 from the discharge end of said first-named pipe that water flowing into said second-named pipe must be taken from the supply in said tank, a return pipe leading from the discharge end of said second-named pipe back to said water supply 50 means, and a check valve in said return pipe, for the purpose specified.
14. In combination with a receptacle containing a heating medium, a water heater positioned in said receptacle in such manner 55 that it is subject to the heating action of said medium, water supply means including a storage tank for said heater, a substantially vertically disposed discharge pipe extending upward through and having its intake end a substantial distance above the bottom of said tank, controlled outlet means in the lower end of said discharge pipe, a pipe connecting said heater with said discharge pipe 60 at a point substantially above said outlet means, a pipe leading from said heater and arranged so that water flowing therein must discharge into the upper portion of said tank, and a hot water circulating system including a pipe having controlled outlet means, said fourth-named pipe leading from the upper portion of said tank and having its intake end sufficiently remote from the discharge end of said third-named pipe that 65 water flowing into said fourth-named pipe must be taken from the supply in said tank, and a return pipe leading from the discharge end of said fourth-named pipe back to said water supply means.
15. In combination with a receptacle containing a heating medium, a water heater positioned in said receptacle in such manner 70 that it is subject to the heating action of said medium, water supply means including a storage tank, a pipe connecting said supply means with said heater, a pipe leading from said heater and arranged so that water flowing therein must discharge into the upper portion of said tank, said respective pipes 75 having openings located at various points, screw plugs normally closing said respective openings whereby upon removal of the plugs, hose or pipes connected with a source of water supply may be temporarily attached and the sediment in said pipes flushed out, and a hot water circulating system, including a pipe having controlled outlet means, said third-named pipe leading from the upper portion of said tank and 80 having its intake end sufficiently remote from the discharge end of said second-named pipe that water flowing into said third-named pipe must be taken from the supply in said tank, and a return pipe leading from the discharge end of said third-named pipe back to said first-named water supply means.
16. In combination with a receptacle containing a heating medium, a water heater positioned in said receptacle in such manner 85 that it is subject to the heating action of said medium, water supply means including a storage tank, a substantially vertically disposed discharge pipe extending upward 90 through and having its intake end a substantial distance above the bottom of said tank, controlled outlet means in the lower end of said discharge pipe, a pipe connecting said heater with said discharge pipe 95 at a point substantially above said outlet means, a pipe leading from said heater and arranged so that water flowing therein must discharge into the upper portion of said tank, and a hot water circulating system including a pipe having controlled outlet means, said fourth-named pipe leading from the upper portion of said tank and having its intake end sufficiently remote from the discharge end of said third-named pipe that 100 water flowing into said fourth-named pipe must be taken from the supply in said tank, and a return pipe leading from the discharge end of said fourth-named pipe back to said water supply means.
17. In combination with a receptacle containing a heating medium, a water heater positioned in said receptacle in such manner 105 that it is subject to the heating action of said medium, water supply means including a storage tank, a pipe connecting said supply means with said heater, a pipe leading from said heater and arranged so that water flowing therein must discharge into the upper portion of said tank, said respective pipes 110 having openings located at various points, screw plugs normally closing said respective openings whereby upon removal of the plugs, hose or pipes connected with a source of water supply may be temporarily attached and the sediment in said pipes flushed out, and a hot water circulating system, including a pipe having controlled outlet means, said third-named pipe leading from the upper portion of said tank and 115 having its intake end sufficiently remote from the discharge end of said second-named pipe that water flowing into said third-named pipe must be taken from the supply in said tank, and a return pipe leading from the discharge end of said third-named pipe back to said first-named water supply means.
18. In combination with a receptacle containing a heating medium, a water heater positioned in said receptacle in such manner 120 that it is subject to the heating action of said medium, water supply means including a storage tank, a substantially vertically disposed discharge pipe extending upward through and having its intake end a substantial distance above the bottom of said tank, controlled outlet means in the lower end of said discharge pipe, a pipe connecting said heater with said discharge pipe 125 at a point substantially above said outlet means, a pipe leading from said heater and arranged so that water flowing therein must discharge into the upper portion of said tank, and a hot water circulating system including a pipe having controlled outlet means, said fourth-named pipe leading from the upper portion of said tank and having its intake end sufficiently remote from the discharge end of said third-named pipe that 130 water flowing into said fourth-named pipe must be taken from the supply in said tank, and a return pipe leading from the discharge end of said fourth-named pipe back to said first-named water supply means.

ly through and having its intake end a substantial distance above the bottom of said tank, controlled outlet means in the lower end of said discharge pipe, a pipe connecting said heater with said discharge pipe at a point substantially above said outlet means, a pipe leading from said heater and arranged so that water flowing therein must discharge into the upper portion of said tank, said second and third-named pipes having openings located at various points, screw plugs normally closing said respective openings whereby upon removal of the plugs, hose or pipes connected with a source of water supply may be temporarily

attached and the sediment in said second and third-named pipes flushed out, and a hot water circulating system including a pipe having controlled outlet means, said fourth-named pipe leading from the upper portion of said tank and having its intake end sufficiently remote from the discharge end of said third-named pipe that water flowing into said fourth-named pipe must be taken from the supply in said tank and a return pipe leading from the discharge end of said fourth-named pipe back to said first-named water supply means. 20 25

JACOB S. ERICKSEN.
